UNITED STATES PATENT OFFICE.

WILLIAM H. HOLLOPETER, OF PORTLAND, OREGON.

CIRCLE-DIVIDING INSTRUMENT.

Application filed May 27, 1925. Serial No. 33,130.

This invention relates generally to drawing instruments, and particularly to means for dividing circles into equal parts.

The first object of this invention is to provide an exceedingly simple and efficient form of a circle dividing instrument wherein any desired number of divisions may be obtained within the limits of the instrument by direct setting of the parts, without requiring any computation on the part of the operator.

The second object is to so construct the device as to make same lend itself to inexpensive manufacture, and in which the setting can be easily made by an unskilled person.

The third object is to construct the instrument that it can readily be taken down for storage or shipping purposes.

The fourth object is to so construct the parts that extreme accuracy can be obtained with very little effort.

These, and other objects, will become more apparent from the specification following as illustrated in the accompanying drawing, in which:

Figure 1 is a plan of the instrument showing it in operation. Figure 2 is an end elevation showing the pencil arm. Figure 3 is a front elevation. Figure 4 is a vertical section taken along the line 4-4 in Figure 1. Figure 5 is an enlarged view of the scale arm. Figure 6 is an enlarged elevation of the dividing head. Figure 7 is a side view of Figure 6 of which Figure 8 is a plan with a portion cut away for clearness. Figure 9 is a rear elevation of Figure 6. Figure 10 is a still further enlarged detail of the tracing wheel.

Similar numbers of reference refer to the same parts throughout the several views.

Referring in detail to the drawings, for the purpose of illustrating the device it is shown on a piece of paper 11 upon which rest its legs 12 which support the round base 13 having a downwardly extending stem 14 and an upwardly extending stem 15 whose uppermost end 16 is threaded. A vertical pin 17 is slidably mounted in the base 13. The stem 15 serves as a pivot for the bar 18 which is preferably provided with bosses 19 for bearing purposes. A thumb nut 20 is placed on the end 16 of the stem 15 to hold the bar 18 in place.

On the end 21 of the bar 18 is slidably placed the marking head 22 which can be clamped in a desired position by means of the thumb screw 23. On the lower side of the marking head 22 is formed the stud 24 on which is pivoted the arm 25 which is held in place by means of the washer 26, and the nut 27. On the under side of the driving end 28 of the arm 25 is formed a boss 29, through which passes the threaded shank 30 of the pin 31 which is provided with a hole 32 for the rod 33. A set screw 34 in the pin 31 is used to clamp the rod 33 in the desired position. A washer 35 and a nut 36 hold the shank 30 in place.

On the marking end 37 of the arm 25 is mounted a pencil arm 38 to which it is hinged by means of the vertical bolt 39 which is threaded into the boss 40. A pencil holder 41 is hinged to the pencil arm by means of the horizontal pin 42. A spring 43 is held by the head of the bolt 39 and urges the pencil arm downwardly. A lead holder 44 is threaded through the split end 45, through which end passes the clamping screw 46. A threaded plunger 47 is used to feed the leads 44 out of the holder 44.

The dividing end 48 of the bar 18 is provided with a serrated edge 49 and carries the slideable dividing head 50, and has a handle 51 on its upper side. On the under side of the head 50 is formed a bracket 52 through which passes the threaded axle 53, on whose threaded end is placed a lock nut 54, preferably knurled, as is the head 55. The latter is provided with graduations 56. A pointer 57 is fastened to the bracket 52 by means of the screws 58. On the axle 53 is mounted a tracing wheel 59 which is held in place by the washer 60 and nut 61.

In one side of the tracing wheel 59 is provided an outer circle of index holes 62 which, in this instance, are twenty-five in number. An intermediate circle of five holes 63 and an inside circle with the one hole 64 are also provided.

Passing vertically through the head 50 is a rod 65 having a number of V grooves 66 formed therein and having a head 67 formed thereon, and also having its end 68 shouldered and threaded to form a pivot for the rocker arm 69, which is held in place by the washer 70 and the nut 71.

The end 72 of the arm 69 carries a small

roller 73 adapted to engage one circle of holes 62, 63 or 64 at one time, depending upon the vertical position of the rod 65. This is determined accurately by the pointed 5 screw 74 which engages the grooves 66.

The end 75 of the rocker arm 69 is provided with a vertical screw 76 on which is hinged the arm 77. The arm 77 can be clamped rigid to the member 69 by means of 10 the screw 76. On the outer end of the arm 77 is mounted the rotatable pin 78 on whose shank 79 are placed the washer 80 and the nut 81.

The hole 82 receives the rod 33 which may 15 be clamped to the pin 78 by means of the screw 83. The spring 84 is attached to the bracket 52 by means of the screw 85 and bears against the arm 69 at its junction with the arm 77.

20 On the side of the head 50, in front of the notches 86 in the serrated edge 49, is threaded the tubular member 87 whose flanged portion 87^A is graduated, as shown. Bearing in the member 87^A and partly in the 25 head 50 is a pin 88 whose shank 89 carries a spring 90 and passes through a hole in the member 87^A and has pinned on its projecting end the knurled head 91 which is provided with an index arm 92 whose point 93 can engage the holes 94 on the member 87^A. An 30 eccentric point 95 is formed on the pin 88 and is adapted to slidably engage the notches 86.

On top of the member 18 alongside of the 35 serrated edge 49 are placed three scales 96, 97 and 98. The circle 99, which is being divided, is indicated on the paper 11, as well as the imaginary circle 100 along which the measurements are made. Readings on the 40 scale are made along the side 101 of the member 50. Notches 102 in the circle 99 indicate the divisions which have been made.

The operation of the device is as follows: Given a circle to divide into forty parts the 45 point of the pin 17 is placed in the center of the circle 99, which is to be divided. The point 95 is now moved and rotated on its axis until the side 101 of the dividing head 50 is on the graduation marked "40" on the 50 scale 97 and the point 93 is in the serrated hole in the member 87^A. The pencil point is now adjusted for height and radius by means of the plunger 47 and the screws 34 and 83. The roller 73 is now moved to the intermediate circle of holes 63 in which there are five holes, as above stated.

When the head 50 is in the position above described, the tracing wheel 59 is adjusted four inches from the center of the circle 60 100. The diameter of the tracing wheel 59 is one unit, which, in this instance, happens to be inches, therefore it follows that it will revolve eight times at every complete journey around the circle 100. Since the wheel 65 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 ing head; a rocker arm mounted on said dividing head; means between said wheel and rocker arm for rocking said arm; and means connecting said rocker arm and said marking means adapted to momentarily deflect said marker from its path at each complete or fractional revolution of said tracing wheel.

4. In a circle dividing instrument, the combination of a central pivot having a paper-engaging point; a bar rotatably mounted on said pivot, one end of said bar having a plurality of scales consisting of sets of calibrations marked thereon, the opposite end of said bar being plain; a marker on the plain end of said bar adjustable with relation to the paper and pivot; a dividing head on the calibrated side of said bar; and a tracing wheel on said dividing head one division of whose circumference, as determined by index holes, is evenly divided into a circle traversed by said tracing wheel when said head is set at a calibration on the corresponding

scale representing the number of divisions desired. 25

5. In a circle dividing instrument, the combination of a central paper-engaging pivot; a flat bar rotatably mounted on said pivot near its middle, said bar having one end calibrated and the same end provided 30 with notches corresponding with said calibrations; a dividing head slidably mounted over the notched portion of said bar; means for adjusting the position of said head on said bar between said notches; a paper-engaging wheel supporting said head, said wheel having a plurality of circles of concentric holes formed in its side; a rocker arm on said head having a roller on one end thereof; means for moving said roller into 35 engagement with the holes of any of said circles; a pencil-holding arm on the plain end of said bar; and a rod connecting said rocker arm and said pencil arm. 40
